TELEVISION RECEIVING SYSTEM

Harold M. Lewis, Great Neck, N. Y., assignor to
 Hazeltine Corporation, a corporation of Delaware

Application August 28, 1937, Serial No. 161,424

4 Claims. (Cl. 178—7.5)

This invention relates to television receiving systems and, more particularly, to such systems including provisions for controlling the background illumination of the reproduced scene.

In accordance with present television practice, a transmitted signal comprises picture- or video-frequency components representative of varying light values in successive areas of an image being transmitted and synchronizing-frequency components which correspond to initiations of successive lines and frames in the scanning of the image. The latter components ordinarily have amplitude values outside of the amplitude range of the video-frequency components. There is usually developed at the transmitter a unidirectional voltage which corresponds to the average background illumination of the scene, but this voltage is lost when the signal is passed through the alternating current amplifiers of the transmitter. However, the signal as received includes a component from which the unidirectional voltage representative of background illumination may be reproduced.

A signal-reproducing device, such as a cathode-ray tube, is employed at the receiver and the cathode ray is deflected therein to scan, in series of parallel lines, a fluorescent screen upon which the image of the transmitted scene is reproduced. The synchronizing-frequency components of the received signal are utilized to control the scanning apparatus so as to synchronize its operation with that of similar apparatus utilized at the transmitter in developing the signal. The intensity of the cathode ray is controlled by the picture- or video-frequency components of the signal, as well as by the unidirectional background illumination voltage developed in the receiver, thereby to reproduce the scene.

Essential functions which must be performed in a television receiving system of the type described, therefore, include deriving from the signal separate line-frequency and frame-frequency synchronizing impulses and a unidirectional bias voltage representative of the average background illumination. Various methods have heretofore been devised for performing these functions, but, in general, they have involved relatively complicated and/or unstable apparatus, or have been otherwise unsatisfactory.

It is an object of the present invention to provide, in a cathode-ray tube television signal-reproducing system wherein the received signal includes combined picture- or video-frequency components, background illumination components,

and synchronizing components having amplitude values outside the amplitude range of the picture components, improved means for deriving from the received signal the synchronizing impulses and a unidirectional control-bias voltage representative of the background illumination. 5

In accordance with the invention, a television signal-receiving system for reproducing a signal including combined picture components and synchronizing components having amplitude values outside the amplitude range of the picture components, the background illumination being represented by the peak value of the signal on one side of its zero axis, comprises a source of bias voltage and a signal-translating stage having an 15 input circuit to which the signal is applied. A rectifier, preferably a diode, is coupled directly to the input circuit for deriving from the signal a bias voltage proportional to the peak value of the signal representing the background illumination. There is included in the circuit of the rectifier impedance means for deriving from the signal impulses corresponding to the synchronizing components. The system also includes means for utilizing the derived impulses for synchronizing the scanning operation of the system and means respective jointly to the two bias voltages for controlling the background illumination of the signal translated by the stage. 20

For a better understanding of the invention, 30 together with other and further objects thereof, reference is had to the following description taken in connection with the accompanying drawing, and its scope will be pointed out in the appended claims. 35

In the accompanying drawing, Fig. 1 is a circuit diagram, partially schematic, of a cathode-ray tube television reproducing system including circuits embodying the present invention and Fig. 2 is a group of curves representing certain operating characteristics of the system of Fig. 1 to aid in the understanding of the invention. 40

Referring now more particularly to the drawing, the system there illustrated comprises a receiver of the superheterodyne type including an 45 antenna and ground system 10—11 connected to a radio-frequency amplifier 12 to which is connected in cascade, in the order named, an oscillator-modulator 13, an intermediate-frequency amplifier 14, a detector and A. V. C. supply 15, a 50 video-frequency amplifier 16, and a cathode-ray signal-reproducing tube 17, constituting the main signal channel of the receiver. The elements or components 10—16 may all be of conventional well-known construction so that detailed illustrations 55

and descriptions thereof are deemed unnecessary herein.

The cathode-ray tube 17 comprises the usual envelope 18 containing, in the order named, a cathode 20, a main or video control grid 21, a screen 22, a first anode 23, a second anode 24, and the usual fluorescent screen 25 at the end of the tube. Line-frequency and picture-frequency electromagnetic deflecting or scanning coils 26 and 27 are disposed about the tube for deflecting the beam in two directions normal to each other. The output of the video-frequency amplifier is connected to the control grid 21 by way of a coupling condenser 28 and leak resistor 29 for controlling the intensity of the cathode-ray in accordance with the video-signal components, as in usual practice. Operating potentials are applied to the electrodes of the tube 17 from a suitable source, such as the battery 30. The unidirectional bias voltage developed by the A. V. C. supply is applied by suitable leads 35 to one or more of the control grids of the tubes in the preceding stages of the system in the conventional manner.

For developing saw-tooth current waves for the coils 26 and 27 to effect scanning of the target 25 by the cathode ray, there are provided a line-frequency generator 31 and a frame-frequency generator 31'. The output of the video-frequency amplifier 16 is coupled to these generators, for maintaining them in proper synchronism with the scanning at the transmitter, by means of rectifying apparatus indicated generally at 32, a synchronizing impulse amplifier 33, and a synchronizing impulse separating means indicated generally at 34. The apparatus indicated at 32, 33, and 34 embodies, or is directly associated with, the present invention and will be hereinafter described in detail. The generators 31 and 31' may be of any well-known or suitable design, such, for instance, as that described in United States Letters Patent No. 2,052,184, granted August 25, 1936.

Since the system thus far described is, in general, conventional and well understood in the art, a detailed explanation of its general operation is deemed unnecessary. Briefly, however, signals intercepted by the antenna circuit 10-11 are selected and amplified in the radio-frequency amplifier 12 and supplied to the oscillator-modulator 13, wherein they are converted to intermediate-frequency signals which, in turn, are selectively amplified in the intermediate-frequency amplifier 14 and delivered to the detector 15. The modulation components of the signal are derived by the detector 15 and are supplied to the video-frequency amplifier 16, wherein they are amplified and from which they are supplied to the control grid 21 of the cathode-ray tube. The A. V. C. bias voltage developed by the detector and A. V. C. supply 15 and applied to the tubes in the preceding stages of the system serves to maintain the signal amplitude at the output 65 of the amplifier 14 within a relatively narrow range, or substantially constant for a wide range of received signal intensities.

With proper operating potentials supplied to the electrodes of the tube 17, an electron beam is emitted from the cathode 20 and its intensity is modulated or controlled by the grid 21 in accordance with the video-frequency voltages impressed thereon. The screen 22 serves to control the average intensity of the beam, while the first and second anodes 24 and 25 co-operate to

accelerate and focus the beam. The saw-tooth current waves developed by the generators 31 and 31' are supplied to the coils 26 and 27 and produce magnetic fields of saw-tooth wave form which serve to deflect the beam vertically and horizontally, thereby causing the beam to trace the well-known rectilinear scanning pattern on the fluorescent screen 25 to reproduce the transmitted scene.

The generators 31 and 31' are synchronized with the corresponding scanning apparatus at the transmitter by the synchronizing impulses appearing in the output circuit of the amplifier 16, these impulses being derived by the apparatus 32, 33, and 34 embodying the present invention. A unidirectional bias voltage representative of the background illumination is also developed by this apparatus and applied to the control grid 21 to control the average illumination of the reproduced scene.

Referring now more particularly to the part of the system embodying the present invention, the rectifying means 32 serves to develop from the signal both the background illumination control unidirectional bias voltage and the synchronizing impulses. The rectifying means 32 comprises a diode 36 connected across the output circuit of the video-frequency amplifier 16 through an impedance, which may comprise resistance means only, but preferably comprises a resistor 37 and inductance 38 in series, as shown, and a source of biasing potential, indicated by the battery 39. The electrical values of the condenser 28 and resistor 29 are very large and provide a large time constant for the rectifier circuit. The battery 39 provides an initial negative bias for the control grid of the cathode-ray tube to ensure proper operation thereof in the absence of a signal, while the impedance elements 37, 38 provide a load or output circuit across which are developed synchronizing impulse voltages free from the picture-frequency voltages, as will be presently further explained.

The amplifier 33 comprises a conventional pentode tube 40 having its input circuit connected across the impedance elements 37 and 38 by way of coupling condenser 41 and leak resistor 42, as shown. The output circuit of this tube includes a blocking resistor 43, a coupling condenser 44, and an impedance network 34, which constitutes the synchronizing impulse separating means. The network 34 is provided with two parallel arms, one including a voltage differentiating circuit comprising a series condenser 45 and resistor 46 and the other including a voltage integrating circuit comprising a series resistor 47 and condenser 48. The input circuits of the frame- and line-frequency generators 31 and 31' are connected across the condenser 48 and resistor 46, respectively, to receive the synchronizing impulses. Operating potentials are applied to the electrodes of the tube 40 from suitable sources, such as batteries 40a. Preferably the scanning generators are designed to operate without synchronization at frequencies slightly lower than the desired operating frequencies, so that they may be easily synchronized and will be unaffected by impulses which occur at improper times.

The operation of the system in accordance with the present invention may best be explained with reference to the curves of Fig. 2. In these curves, which represent the wave forms of particular signals developed at different points in the sys-

tem, only a few line-frequency cycles are indicated, the broken lines indicating omissions. Curves W, G, and B represent the signal voltage which, in the absence of the background control embodying the invention, would appear between the grid 21 and cathode 20 of the cathode-ray tube 17 for: a white background having a vertical black bar; a grey background having two vertical bars, one white and one black; and a black background having a vertical white bar, respectively, each line including a sudden change from positive to negative to represent a sudden change from white to black, or vice versa. At the end of each line period there is a negative impulse or pedestal, as indicated at N, occurring during the line retrace or so-called block-out scanning period of the cathode ray. A synchronizing impulse I occurs at the initiation of each retrace period. Thus, the picture components are combined with the synchronizing components and the latter have amplitude values which are outside of the amplitude range of the picture components. The signal represented by the curves W, G, B, does not include a unidirectional voltage component representing changes in background illumination, since the alternating current wave centers itself about its axis and the unidirectional voltage is lost when the signal is passed through alternating current amplifier stages of the system. However, this signal does include a component representative of the background illumination, this component being the peak value of the signal on the side of its axis representing black.

Curve A of Fig. 2 illustrates the grid voltage (e_g)—vs.—cathode-ray current (i_{cr}) characteristic of the reproducing tube 17, it being apparent that there is a substantially linear relation between the cathode-ray current and its control-grid voltage over the range of operation. It is assumed that the luminosity of the fluorescent screen is proportional to the current in the ray and that point b, near cutoff, represents the bias voltage (e_b) required for black, the point g, that required for gray, and the point w, near zero bias, that required for white. For maximum sensitivity, the video modulation voltage is applied to the grid with sufficient amplitude to control the cathode-ray current between the limits b, w, thereby to produce the variation from black to white. It will be obvious that a unidirectional control voltage is required for establishing the bias at the points w, g, and b for white, grey, and black subjects, respectively, in order that proper background illumination of the reproduced image may be obtained. That is, the signal when applied to the control grid 21 should be of the form indicated at W₁, G₁, B₁. It will be seen that, with such a background illumination component superimposed on the video signal, operation of the signal-translating stage comprising tube 17 is, at all times, automatically maintained over substantially the entire useful portion of the tube characteristic.

For this purpose, the control grid 21 is initially negatively biased by the battery 39 approximately to the point b. The diode 36 is coupled directly to the input circuit of the signal-translating stage comprising tube 17 and derives from the signal output of the amplifier 16 (curves W, G, B), a positive unidirectional voltage equal to the peak value of the signal on the black side of its zero axis which appears across resistor 29. This latter positive voltage is applied to the con-

trol grid 21 in opposition to the initial fixed negative bias from battery 39. The resultant video signal applied to the control grid 21, therefore, is of the desired form indicated by the curves W₁, G₁, B₁, with the unidirectional voltage restored. The cathode-ray tube current, therefore, is of a form illustrated by the curves W₂, G₂, B₂ and the reproduced scene includes the unidirectional or low-frequency background illumination components determined jointly by the fixed negative bias and derived positive bias as well as the video or high-frequency picture components of the signal.

Curve B of Fig. 2 illustrates the characteristics of the rectifier 36, the abscissae representing the applied alternative voltage (e_a) and the ordinates representing the load current (i_a). It will be seen that the diode passes current only during the occurrence of the synchronizing impulses, this being determined by the large time constant circuit comprising condenser 28 and resistor 29. Hence, during each of the synchronizing impulses, current flows through the impedance elements 31, 38 in series with the diode 36 and there is developed across these elements synchronizing impulses or voltages free from the picture components of the signal.

Assuming the well-known type of synchronizing signal to be employed, commonly known as the serrated signal, the line impulses and frame impulses occur continuously and independently, the frame impulses being interrupted or serrated to provide intervals for the line impulses. The impedance network 34 included in the output circuit of the tube 40 is designed to effect the separation of these line and frame impulses. In accordance with the well-known principles of differentiation, double impulses at the line frequency and free from the frame impulses are developed across the resistor 46. These impulses are so applied to the generator 31 as to maintain it in synchronism. In accordance with the well-known principles of integration, impulses at the frame frequency, free from line impulses, are developed across the condenser 48 and the latter impulses are similarly applied to the generator 31' to maintain it in synchronism.

The invention, while intended for the reception of signals from which the direct current component has been removed, is equally advantageous for the reception of signals in which this component is transmitted and retained throughout the receiving system including the video-frequency amplifiers. In this case utilization of the invention permits the operation of the cathode-ray tube 17 with its cathode grounded, under which condition the direct current component is ordinarily lost due to the coupling condenser which must be employed between the last video-frequency amplifier stage and the grid of the cathode-ray tube. In such an arrangement the present invention is utilized to restore the direct current component by means of the background control including the rectifier 36, as described above. It is emphasized that the curves of Fig. 2 illustrate the necessity of having the direct current component present prior to both the application of the signal to the grid of the cathode-ray tube and prior to the separation of the synchronizing signals from the video-frequency signals. The diode circuit arrangement of this invention is effective to insert the direct current component for both of these purposes and simultaneously accomplishes the separation of the

synchronizing signals from the video-frequency signals.

Obviously, the system of the present invention may be employed for signals having types of synchronizing impulse modulation other than the so-called serrated impulse type. For such other types of modulation the apparatus employer for separating the line- and frame-synchronizing impulses may be suitably modified. For example, 10 where the line- and frame-synchronizing impulses are characterized by differences in their amplitudes, they may be separated by amplitude responsive means, as, for example, a properly biased vacuum tube arrangement.

15 It will be clear to those skilled in the art that the arrangement may be simplified to omit amplifier 33 and incorporate the circuits for separating the frame impulses from the line impulses directly in the circuit of the diode 36, that is, 20 replacing the elements 37, 38.

25 It will be seen from the above description that the present invention provides an efficient and relatively simple system whereby a single means serves simultaneously to develop from the detected signal a background illumination control-bias voltage as well as synchronizing impulses.

30 While there has been described what is at present considered the preferred embodiment of the invention, it will be obvious to those skilled in the art that various changes and modifications may be made therein without departing from the invention, and, therefore, it is aimed in the appended claims to cover all such changes and 35 modifications as fall within the true spirit and scope of this invention.

What is claimed is:

1. A television signal-receiving system for reproducing a signal including combined picture 10 components and synchronizing components having amplitude values outside the amplitude range of the picture components, the background illumination being represented by the peak value of the signal on one side of its zero axis, comprising 15 a source of bias voltage, a signal-translating stage having an input circuit to which said signal is applied, a diode rectifier coupled directly to said input circuit for deriving from said signal a bias voltage proportional to said peak value 20 of said signal, impedance means in circuit with said rectifier for deriving from said signal impulses corresponding to said synchronizing components, means for utilizing said synchronizing impulses for synchronizing the scanning operation 25 of the system, and means responsive jointly to said bias voltages for controlling the background illumination of the signal translated by said stage.

2. A television signal-receiving system for reproducing a signal including combined picture 30 components and synchronizing components having amplitude values outside the amplitude range of the picture components, the background illumination being represented by the peak value 35 of the signal on one side of its zero axis, comprising a source of bias voltage, a signal-trans-

lating stage having an input circuit to which said signal is applied, a rectifying means for deriving from said signal a bias voltage proportional to said peak value of said signal comprising a diode rectifier coupled directly to said input circuit, an input circuit including a large capacitance element and an output circuit including a high resistance element, impedance means in series with said rectifier for deriving from said signal impulses corresponding to said synchronizing 10 components, means for utilizing said synchronizing impulses for synchronizing the scanning operation of the system, and means responsive to the resultant of said two bias voltages for controlling the background illumination of signal 15 translated by said stage.

3. A television signal-receiving system for reproducing a signal including combined picture components and synchronizing components having amplitude values outside the amplitude range 20 of the picture components, the background illumination being represented by the peak value of the signal on one side of its zero axis, comprising a source of bias voltage, a signal-translating stage having an input circuit to which said signal is 25 applied, a diode rectifier coupled directly to said input circuit for deriving from said signal a bias voltage proportional to said peak value of said signal, impedance means comprising a resistance and an inductance in series with said rectifier 30 for deriving from said signal impulses corresponding to said synchronizing components, means for utilizing said synchronizing impulses for synchronizing the scanning operation of the system, and means responsive to the resultant of 35 said two bias voltages for controlling the background illumination of the signal translated by said stage.

4. A television signal-receiving system for reproducing a signal including combined picture 40 components, and synchronizing components having amplitude values outside the amplitude range of the picture components, the background illumination being represented by the peak value of the signal on the side of its axis corresponding 45 to black, comprising a time constant circuit for translating said signal including a series connected condenser and resistor across which the composite signal is impressed, a signal-reproducing device having input electrodes coupled directly to said resistor, a circuit connected in parallel with said resistor including a diode rectifier for developing a bias voltage across said resistor proportional to said peak value of said signal 50 and an impedance element for deriving from said signal impulses corresponding to said synchronizing components separate from said picture components, means for utilizing the picture components impressed across said resistor for reproducing a scene and for utilizing said bias voltage 55 for controlling the background illumination thereof, and means for utilizing said separate synchronizing pulses for synchronizing the scanning operation of the system.

HAROLD M. LEWIS. 65
